Robert Chieda, 3 Northgate, Westport, Conn.

Filed Feb. 5, 1964, Ser. No. 78,529

Term of patent 14 years

(Cl. D26—1)

FIG. 2

FIG. 1

FIG. 3

FIG. 4

FIG. 5

FIGURE 1 is a perspective view of a cover for an electrical connector for distribution lines, showing my new design, which defines a hollow interior volume for receiving an electrical connector therein and may be seen to be substantially symmetrical about a vertical, longitudinal median plane.

FIGURE 2 is a top plan view of my cover design.

FIGURE 3 is a full side elevation view of this cover.

FIGURE 4 is an end elevational view; and

FIGURE 5 is a bottom plan view of this cover design.

I claim:

The ornamental design for a cover for an electrical

connector for distribution lines, substantially as shown and described.
